(57) **CLAIM**

The ornamental design for a portable data entry tablet, as shown and described.

DESCRIPTION

FIG. 1 is a perspective view of a portable entry data tablet showing my new design;

FIG. 2 is a front plan view thereof;

FIG. 3 is a rear plan view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the drawings represent portions of the portable data entry tablet that form no part of the claimed design.
